ORNAMENTAL IRON SCROLL BENDER

Michael J. Ahern, Inglewood, Calif.

Application November 25, 1955, Serial No. 548,843

8 Claims. (Cl. 153—40)

This invention relates to means for bending metal bars and is specifically directed to a power-actuated apparatus for forming bar stock into spiral scrolls for the fabrication of ornamental iron work and the like.

Since ornamental iron work is customarily fabricated entirely by hand by highly skilled artisans, the cost is correspondingly high. There is a pressing need, therefore, for power-actuated machinery to reduce the amount of handwork involved.

While many ornamental iron scrolls consist of a single flat spiral turn of 360° or less, nearly every ornamental iron assembly includes several scrolls having spiral turns extending up to two complete revolutions. The present invention provides a compact power-actuated apparatus that may form a spiral scroll of two complete spiral turns in a single continuous bending operation. This bending operation may be carried out with high rapidity and requires no special skill whatsoever on the part of the operator.

The difficulty in attempting to form a flat spiral scroll of two turns is that when the first turn is being formed, there is interference by the forming surfaces that are required for the subsequent second turn. The invention meets this problem by using two separate rotary forming dies comprising an inner rotary die for the initial turn and an outer rotary die for the second turn, these two dies being adapted for axial movement relative to each other.

At the start of a forming operation, the outer die is in a position offset from the plane of rotation of the inner die to avoid interfering with the bar stock during the initial forming operation by the inner die. If the scroll to be formed has only one spiral turn or less, the outer die remains in its offset position out of contact with the bar stock. If the scroll to be formed is a spiral extending over more than 360°, however, the outer die moves axially into the plane of rotation of the inner die to carry out the latter part of the forming operation and does so in a time manner to permit the scroll to be formed in one continuous operation.

The apparatus of the preferred practice of the invention is further automatic in providing means that may be preset to stop the rotation of the two forming dies at any predetermined point throughout a range of two complete revolutions. For this purpose the preferred practice of the invention includes a clutch for driving the two rotary dies in combination with a rotary stop gauge that may be adjusted to disengage the clutch at selected points in the range of two revolutions.

A feature of the preferred practice of the invention is the provision of a rotary stop gauge that is operatively connected with the two dies for rotation simultaneously therewith and that is provided with a clockspring or the equivalent. The clockspring serves to return the rotary stop gauge to its starting position automatically after each forming operation and since the two dies are operatively connected to the rotary stop gauge, the two dies

2

are also returned automatically to their starting positions.

In the procedure of forming bar stock by rotary die means, it is necessary to hold the bar stock against rotation with the die means thereby to cause the bar stock to wrap around the spiral forming surfaces of the die means. In this regard, a feature of the preferred practice of the invention is the provision of a special holding roller to block any tendency of the bar stock to swing laterally out of its normal feed position. At the start, the holding roller is positioned relatively close to the inner rotary die to cause proper wrapping action of the bar stock and then automatically shifts outward for subsequent cooperation with the forming surfaces of the outer rotary die. As will be explained, the holding roller is not power-actuated and is not shifted by power but, nevertheless, is so mounted on a fixed guide means that it automatically makes the required outward shift in proper timing in reaction to the forming operation itself.

A further feature of the invention is that the two rotary dies are replaceably mounted in the apparatus. This provision makes it possible to use a series of interchangeable dies.

The various features and advantages of the invention may be understood from the following detailed description taken with the accompanying drawings.

In the drawings, which are to be regarded as merely illustrative:

Figure 1 is a plan view of the presently preferred embodiment of the invention;

Figure 2 is a view of the apparatus as seen along the line 2—2 of Figure 1, with parts broken away to reveal concealed structure;

Figure 3 is a view similar to Figure 2 but taken at 90° therefrom;

Figure 4 is a horizontal sectional view taken as indicated by the line 4—4 of Figure 3, showing the rotary stop gauge as seen from above;

Figure 5 is a horizontal section view taken as indicated by the line 5—5 of Figure 2, showing the mechanism for raising the outer rotary die to the plane of rotation of the inner rotary die;

Figure 6 is a sectional view of the same mechanism taken along the line 6—6 of Figure 5;

Figure 7 is a perspective view of a replaceable inner rotary die;

Figure 8 is a plan view of an ornamental iron scroll that may be produced by the invention; and

Figure 9 is a plan view of an ornamental iron assembly incorporating a number of scrolls such as shown in Figure 8.

General arrangement

The fixed structure of the presently preferred embodiment of the invention includes a rectangular four-legged frame 10 carrying a top plate 12 and a shelf 14. The structure between the top plate 12 and the shelf 14 is surrounded by a housing 15, one side of which has a sliding door 16 (Figure 3). The top plate 12 has a circular opening 18 therein which registers with what may be termed a yoke, generally designated 20, which is mounted on the underside of the top plate 12. As best shown in Figures 5 and 6, the yoke 20 has two spaced upright arcuate walls 22 which are interconnected by a bottom wall 24.

The principal moving parts of the apparatus include: an inner rotary die 25 which is separately shown in Figure 7 and which is normally mounted on the upper end of a driven shaft 26, as shown in Figure 6; a clutch 28 in the form of an axially slid able collar for releasably connecting the driven shaft 26 to the upper end of a continuously rotating drive shaft 30; an angular lever 32

for controlling the clutch 28; an adjustable rotary stop gauge, generally designated 34 (Figures 3 and 4) that is operatively connected to the driven shaft 26 to make one rotation when the driven shaft makes two rotations, which stop gauge has a limit stop arm 35; an adjustable stop arm 36 on the stop gauge 34 to operate the clutch lever 32 for automatically terminating a forming operation; a spiral clockspring 38 operatively connected to the rotary stop gauge for the purpose of returning both the rotary stop gauge and the driven shaft 26 to their original starting positions after a forming operation is completed; an outer rotary die 40 which is slidably mounted on the upper end of the drive shaft 26, as best shown in Figure 6, for movement from a normal retracted position below the inner rotary die 25 to an effective position in the plane of rotation of the inner die, this outer rotary die having an upright spiral rib 41 to provide a spiral forming surface and having a peripheral notch 42 (Figure 1) for cooperation with a fixed lug 43; a collar 44 riding on a coiled spring 45 inside the yoke 20 to lift the outer rotary die to its upper position; a forked control lever 46 adapted for releasable engagement with a shoulder 48 of an upright bar 50 to hold the collar 44 in its normal lower position; and a holding roller 52 (Figures 1 and 3) to keep the bar stock from rotating with the rotary dies, this holding roller being carried by a laterally extending arm 54 of a carriage 55 that is slidably mounted on a guide or rail 56.

Operation

To make a scroll having a spiral turn of approximately 360°, such as the scroll 60 at one end of the piece of ornamental iron shown in Figure 8, the adjustable stop arm 36 of the rotary stop gauge 34 is positioned at approximately 180° from the desired effective position of the arm. Since the rotary stop gauge rotates at only half the rate of the forming dies, this 180° position represents one full turn of the driven shaft 26 that rotates the two dies. The control lever 46 is then lifted into engagement with the shoulder 48 against the opposition of the spring 45 to retract the spring-pressed collar 44 to its normal lower position.

The operator then uses his right hand to pick up a metal bar B, uses the bar to push the carriage 55 back to its normal starting position shown in Figure 1 and then inserts the end of the metal bar into a radial slot 62 in the inner die 25, which radial slot is best shown in Figure 7. At this position, the metal bar rests against the holding roller 52 as shown in Figure 1.

When the metal bar is properly positioned in this manner, the operator uses his left hand to raise the clutch control lever 32 to its upper effective position to cause the clutch 28 to connect the driven shaft 26 with the continuously rotating drive shaft 30. The inner die 25 rotates counterclockwise as viewed in Figure 1 and with the holding roller 52 preventing corresponding rotation of the metal bar B, the metal bar wraps itself around the spiral forming surface of the inner rotary die.

When the inner die 25 has rotated approximately 360°, the adjustable stop arm 36 of the rotary stop gauge 34 swings against the clutch control lever 32 to cause disengagement of the clutch 28. Since the forming operation is carried out against the opposition of the clock spring 38, the disengagement of the clutch 28 to free the driven shaft 26 from the continuously rotating driven shaft 30 results in the clock spring returning both the rotary stop gauge and the two forming dies to their normal starting positions.

To form a spiral scroll of more than 360° but no more than two complete rotations, such as the scroll 64 at one end of the ornamental iron bar in Figure 8, the adjustable stop arm 36 is registered with the limit stop arm 35 to permit one complete rotation of the rotary stop gauge and two complete rotations of the forming dies. The forked control lever 46 is engaged with the shoulder 48 in the usual manner. The operator uses the metal bar to

push the carriage 55 back to its normal starting position, and inserts the end of the bar into the forming die slot 62 in the usual manner.

Holding the metal bar in position with his right hand, the operator lifts the clutch control lever 32 with his left hand to start the forming operation and then immediately uses his left hand to tap or push the forked lever 46 out of engagement with the shoulder 48. The release of the forked lever from the shoulder 48 permits the spring 45 to urge the collar 44 upward against the outer forming die 40 but the outer forming die is in a downwardly retracted position because the fixed lug 43 blocks its upward path.

For approximately the first 360° of rotation of the two forming dies the metal bar wraps itself around the inner rotary die 25 with no possibility of interference by the outer die 40 and then, as the wrapping action approaches the end of the spiral forming surface of the inner die, the recess 42 in the outer die rotates into register with the fixed lug 43 to permit the outer rotary die to be snapped upward by the force of the spring 45. At this upper position, the outer forming die 40 operates in the same plane as the inner rotary die. The upward shift of the outer rotary die 40 is timed to permit the forming operation to continue without interruption, the metal bar wrapping itself around the forming surfaces of the two dies in rapid succession.

During this forming operation, the holding roller 52 effectively serves its purpose of preventing rotation of the metal bar and of causing the metal bar to wrap around the spiral forming surfaces of the two rotary dies. As the radius of the forming action increases during the second rotation of the two rotary dies, the roller 52 shifts to the left as viewed in Figure 1 to continue its cooperation with the metal bar.

When the two revolutions of the rotary dies are completed, the stop arms of the rotary stop gauge move against the clutch control lever to disengage the clutch and the clock spring 38 returns the rotary stop gauge and the two rotary dies to their starting positions.

It is apparent that the two operations described above on the two ends of a bar may be performed in rapid succession to produce the double or reverse scroll shown in Figure 8. Any number of such scrolls can be formed in succession with perfect duplication in each instance. Figure 9 shows how such scrolls may be assembled together in the usual manner in the fabrication of ornamental iron. With a series of such interchangeable inner rotary dies available and a matching series of outer rotary dies, scrolls of various dimensions and curvatures may be readily formed, and by wrapping flat stock around the rotary dies, various scrolls of intermediate dimensions and curvatures can be obtained.

Détails of construction

The mechanism of the apparatus is energized by a suitable motor 64 through reduction gearing in a gear case 65 and the drive shaft 30 extends upward from this gear case. The upper end of the drive shaft 30 has a pair of diametrical lugs 66 which may be formed by a suitable cross pin and the lower end of the driven shaft 26 has a similar pair of diametrical lugs 68.

The clutch collar 28 is slidably telescoped over the ends of two shafts 26 and 30 and has longitudinal slots 70 in constant engagement with the two lugs 68 and additionally is formed with a pair of diametrically opposite clutch teeth 72 for engagement with the lugs 66 of the drive shaft 30. It is apparent that when the clutch collar is held in its upper position shown in Figure 2 with the teeth 72 out of engagement with the lugs 66, the driven shaft 26 will be disengaged from the drive shaft 30. On the other hand, when the clutch collar is lowered into engagement with the lugs 66, it interconnects the two shafts for rotation in unison.

The clutch control lever 32 fulcrums on a pivot pin

74 carried by a pair of fixed ears 75 and is provided with a suitable knob or handle 76 on its outer end. The inner arm 78 of the clutch control lever is forked at its end to engage a circumferential groove 80 in the clutch collar 28.

It is contemplated that when the clutch lever 32 is raised to its effective position for lowering the clutch collar 28 into engagement with the lugs 66, the clutch lever will be frictionally retained in this upper position until it is moved to its lower release position by an arm of the rotary stop gauge 34 at the end of a forming operation. Any suitable arrangement may be employed for yieldingly maintaining the clutch lever 32 in its upper position.

In the present embodiment of the invention, a suitable detent means is provided for this purpose, which detent means includes a short fixed bar 82 (Figures 2 and 3) having an upper detent notch 84 for releasably seating the clutch lever 32 at its upper position and having a second similar detent notch 85 to seat the clutch lever at its lower position. The clutch lever 32 is constantly pressed lightly against the detent bar 82 by means of a suitable coiled spring 86 that is best shown in Figure 3. One end of the coiled spring 86 is connected to the clutch lever and the other end is connected to a fixed post 88 that extends upward from the shelf 14.

The adjustable rotary stop gauge 34 is carried by a base casting 90 that is mounted on the shelf 14 by means of suitable bolts 92. This base casting is formed with an upwardly extending boss 94 in which is mounted an upright spindle 95. The stop gauge is in the form of a wheel journaled on the spindle 95 and is formed with peripheral sprocket teeth 96 by means of which it may be driven simultaneously with the driven shaft 26 but at half the rate of rotation. The sprocket teeth 96 are engaged by a sprocket chain 98 driven by a relatively small sprocket 100 on the driven shaft 26.

The rotary stop gauge 34 has a downwardly extending hub 102 which is engaged by the previously mentioned clock spring 38. As best shown in Figure 4, the outer end of the clock spring is anchored by an upright stop post 104 that extends upward from the base casting 90. The clock spring 38 is confined by a suitable cage comprising radial arms 105 that are upwardly bent at their outer ends, the radial arms being mounted on the boss 94 of the base casting.

The rotary stop gauge 34 has the previously mentioned radial stop arm 35 integral therewith. The second adjustable stop arm 38 is journaled on the spindle 95 and is apertured to receive a retaining pin 106 which retaining pin is looped to form a convenient handle. The rotary stop gauge has a circumferential series of bores 108 in its upper face to receive the retaining pin 106. Thus it is a simple matter to use the retaining pin 106 to position the arm 36 at selected angular positions relative to the body of the rotary stop gauge.

Figure 4 shows the adjustable stop arm 36 positioned relative to the rotary stop gauge body to cause disengagement of the clutch after approximately 360° of forming rotation. When the clutch is engaged, the rotary stop gauge rotates counterclockwise as viewed in Figure 4 until the stop arm 36 reaches the clutch control lever 32 and rocks the clutch control lever out of its effective position into its lower ineffective position to cause disengagement of the clutch. The stop arm 35 that is fixedly carried by the rotary stop gauge 34 cooperates with the stop post 104 to determine the starting position of the rotary stop gauge as well as the starting positions of the two rotary forming dies. In addition, the stop arm 35 will make contact with the clutch 32 to stop the forming operation at the end of two complete rotations of the forming dies and thus serves as a safeguard in the event that the adjustable stop arm 36 is absent or is not effectively secured by the retaining pin 106.

As best shown in Figure 6, the driven shaft 26 extends upward through a suitable bearing sleeve 110 formed by the yoke 20. The upper end of the driven shaft 26 above the yoke is formed with an enlargement 112 of square cross section and the stem 114 (Figure 7) of the inner rotary die 25 seats removably in an axial bore 115 in this enlargement. The inner rotary die 25 may be secured in position by a removable cross pin 116.

The outer rotary die 40 has an extensive hub 118 with a passage 120 of square cross section therethrough (Figure 6) by means of which the outer rotary die is slidably mounted on the shaft enlargement 112 for rotation therewith and for axial movement thereon. Normally the outer rotary die 40 is positioned by gravity against the bottom wall 24 of the yoke. A thin fixed sleeve 122 embedded in the bottom wall of the yoke surrounds the hub 118 and serves as a guide means for the previously mentioned spring-pressed collar 44.

The previously mentioned forked control lever 46 may be made of a pair of bars held together by bolts 124 as shown in Figure 5 and may be operatively connected to the spring-pressed collar 44 by a pair of angular links 125. The forked control lever 46 is fulcrumed by a pivot bolt 126 in a pair of ears 128 integral with the yoke 20. The outer end of the forked control lever is movable in a guide slot defined by the previously mentioned upright bar 50 and a second similar bar 130 (Figure 3) and the lower limit position of the lever in this slot is determined by an adjustable stop screw 132.

The stop screw 132 threads into a fixed nut 134 and may be secured in adjusted position by a second lock nut 135. When the forked control lever 46 is disengaged from the shoulder 48, it drops against the stop screw 132 under the force of the coiled spring 45 so that the stop screw 132 determines the level to which the outer rotary die 40 is lifted by the coiled spring. The stop screw is adjusted of course, to place the upper position of the outer rotary die 40 on the same level as the inner rotary die 25.

My description in specific detail of the presently preferred embodiment will suggest various changes, substitutions, and other departures from my disclosure that properly lie within the spirit and scope of the appended claims.

I claim:

1. In an apparatus for bending a bar into the form of a spiral scroll, the combination of: an inner rotary die having a forming surface of increasing radius of curvature corresponding to an angle of rotation of not substantially more than 360°, an outer rotary die rotatably mounted on the same axis as the inner die, said outer die having a forming surface continuing the increase in radius of curvature, said two dies being relatively movable axially between an initial disposition in digerent planes of rotation and a second disposition in the same plane of rotation; actuating means including a clutch to rotate said two dies in unison for a forming operation; a control for said clutch movable between a clutch-engaging position and a clutch-disengaging position; a rotary stop gauge operatively connected with said dies to rotate simultaneously therewith from a starting position and to engage said clutch control after a predetermined amount of rotation of the two dies to cause the clutch control to shift from its engaging position to its disengaging position; and spring means to oppose rotation of said stop gauge out of said starting position by said actuating means and to return the stop gauge to said starting position when said clutch is disengaged thereby to automatically return both the inner and outer dies to their starting position after a forming operation.

2. An apparatus as set forth in claim 1 in which said rotary stop gauge has an element rotatably adjustable thereon to engage said clutch control whereby the predetermined amount of rotation may be varied.

3. In an apparatus for bending a bar into the form of a spiral scroll, the combination of: an inner rotary die

having a forming surface of increasing radius of curvature corresponding to an angle of rotation of not substantially more than 360° , an outer rotary die rotatably mounted on the same axis as the inner die, said outer die having a forming surface continuing the increase in radius of curvature, said outer die being axially movable between a normal position out of the plane of rotation of said inner form and an operating position in said plane; yielding means to urge said outer form axially from its normal position to its operating position; fixed means cooperative with said outer die to prevent movement of the outer die out of its normal position into its operative position until the outer die rotates by a predetermined amount; manually releasable means normally restraining said outer die at its normal position to make said yielding means ineffective when said outer die has rotated by said predetermined amount; actuating means including a clutch to rotate said two dies in unison from a starting position for a forming operation; a control for said clutch movable between a clutch-engaging position and a clutch-disengaging position; a rotary stop gauge operatively connected with said dies to rotate simultaneously therewith from a starting position and to engage said clutch control after a predetermined amount of rotation of the two dies to cause the clutch control to shift from its engaging position to its disengaging position; and spring means to oppose rotation of said stop gauge by said actuating means out of said starting position and to return the stop gauge to said starting position and thereby automatically return both the inner and outer forms to their starting position after a forming operation.

4. In an apparatus for bending a bar into the form of a spiral scroll, the combination of: an inner rotary die having a forming surface of increasing radius of curvature corresponding to an angle of rotation of not substantially more than 360° , an outer rotary die rotatably mounted on the same axis as the inner die, said outer die having a forming surface continuing the increase in radius of curvature, said two dies being relatively movable axially between an initial disposition in different planes of rotation and a second disposition in the same plane of rotation; means to rotate said inner die through a first stage of approximately 360° and to rotate both of the dies in unison through a second stage of continued rotation with said two dies at their initial disposition during the first stage; means to relatively shift said two dies from their initial disposition to their second disposition at the end of said first stage; a fixed guide means; a carriage movable along said guide means; a holding roller carried by said carriage for contact with the side of said bar to prevent rotation of the bar by said dies, said carriage being movable along said guide means from a starting position, said holding roller being within the maximum radius of said outer die at said starting position of the carriage.

5. In an apparatus for bending a bar into the form of a spiral scroll, the combination of: an inner rotary die having a forming surface of increasing radius of curvature corresponding to an angle of rotation of not substantially more than 360° , an outer rotary die rotatably mounted on the same axis as the inner die, said outer die having a forming surface continuing the increase in radius of curvature, said outer die being movable axially between an initial position in a different plane of rotation from said inner die and a second position in the same plane of rotation; power means to rotate said inner die through a first stage of approximately 360° with both dies at their initial positions during the first stage and to rotate both of the dies in unison through a second stage of continuing rotation; means to shift said outer die from its initial position to its second position at the end of said first stage; a clutch to operatively connect said power means to said two dies for rotation thereof; spring

means to oppose rotation of said two dies through said two stages; and means to disengage said clutch in response to a predetermined amount of rotation of the two dies to terminate said second stage and to permit said spring means to rotate the two dies back to their starting positions.

6. An apparatus as set forth in claim 5, in which said means to disengage said clutch is adjustable with respect to the amount of rotation of the two dies to which it responds for adjustment of the degree of which the two dies bend a bar.

7. In an apparatus for bending a bar into the form of a spiral scroll, the combination of: a support structure having a top plate to serve as a rest for a bar during a forming operation, said top having an aperture therein; an inner rotary die having a forming surface of increasing radius of curvature corresponding to an angle of rotation of not substantially more than 360° , said inner rotary die being positioned above said aperture and above the plane of said top plate with its axis of rotation perpendicular to the top plate; an outer rotary die rotatably mounted on the same axis as the inner die, said outer die having a forming surface continuing the increase in radius of curvature, said outer die being movable axially through said aperture from a lower position below the plane of the surface of said top plate and an upper position adjacent said inner die to serve as a continuation of the inner die; yielding means urging said outer die from its lower position to its upper position; a first manually releasable means to hold said outer die at its lower position in opposition to said yielding means and a second means to hold said outer die in its lower position in opposition to said yielding means, said second means being releasable in response to a predetermined amount of rotation of said inner rotary die to cause movement of said outer rotary die to its upper position to continue the bending of a bar after initial bending of the bar by said inner rotary die.

8. In an apparatus for bending a bar into the form of a spiral scroll, the combination of: an inner rotary die having a forming surface of increasing radius of curvature corresponding to an angle of rotation of not substantially more than 360° , an outer rotary die rotatably mounted on the same axis as the inner die, said outer die having a forming surface continuing the increase in radius of curvature, said outer die being movable axially between an initial position in a different plane of rotation from said inner die and a second position in the same plane of rotation; power means to rotate said inner die through a first stage of approximately 360° with both dies at their initial positions during the first stage and to rotate both of the dies in unison through a second stage of continuing rotation; means to shift said outer die from its initial position to its second position at the end of said first stage; a clutch to operatively connect said power means to said two dies for rotation thereof; spring means to oppose rotation of said two dies through said two stages; and means to disengage said clutch; said disengaging means including a rotary member operatively connected with said two dies for rotation simultaneously therewith and a stop means carried by said rotary member to disengage said clutch, said stop means being adjustable on said rotary member to vary the extent of rotation of the two dies by said power means.
